CLINTON O. HARRINGTON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL RELAY.

1,400,603.

Specification of Letters Patent. Patented Dec. 20, 1921.

Application filed January 31, 1920. Serial No. 355,499.

To all whom it may concern:

Be it known that I, CLINTON O. HARRINGTON, a citizen of the United States, residing at Edgewood borough, in the county of Allegheny and State of Pennsylvania, have invented certain new and useful Improvements in Electrical Relays, of which the following is a specification.

My invention relates to electrical relays, and particularly to relays of the type wherein means are provided for increasing the resistance of the circuit of the energizing winding when the relay armature is closed, and decreasing the resistance of this circuit when the armature is open. This variation in resistance can usually be most conveniently effected by opening and closing a shunt around a resistance element which is included in the circuit of the energizing winding, and in the illustrated form of my invention this resistance element is part of the energizing winding itself, although this particular construction is not essential to my invention. In the illustrated form of my invention, the relay is provided with a low resistance "pick-up" winding, and a high resistance "holding" winding, and the shunt is placed around the latter winding and is controlled by the relay armature.

One object of my invention is the provision of means for closing this shunt, during the opening movement of the armature, when the armature reaches such position that it cannot be closed by current of "release" value in the pick-up winding, and for keeping the shunt closed until the armature reaches a point near the end of its stroke while closing. That is, the shunt is closed when the armature is at one point during the opening movement, and is opened when the armature is at another point during the closing movement, the latter point being nearer to the fully closed position than the former.

I will describe one form of relay embodying my invention, and will then point out the novel features thereof in claims.

In the accompanying drawing, Figure 1 is a view showing in side elevation one form of relay R embodying my invention, the windings of the relay being connected with a track circuit which is illustrated diagrammatically. Fig. 2 is a view showing an auxiliary magnet and armature included in the relay shown in Fig. 1, and looking at the

same from the left hand side as viewed in Fig. 1. Fig. 3 is a fragmental view of a contact C included in the relay R, showing the condition of this contact when the armature is in a certain position while opening. Fig. 60 Fig. 4 is a view similar to Fig. 3 but showing the condition of the contact C when the armature is in the fully opened position. Fig. 5 is a view similar to Fig. 3 but showing the condition of the contact C when the armature is in a certain position while closing. 65

Similar reference characters refer to similar parts in each of the several views.

Referring first to Fig. 1, the relay, which is designated as a whole by the reference character R, comprises, a plate 1 of insulating material which carries an electromagnet E. This electromagnet comprises a core 3 of magnetizable material which passes through the plate 1 and terminates in a 70 pole-piece 3^a on the under side of the plate. Only one core and pole-piece are shown in the drawing, but in accordance with usual practice the relay is provided with two such members, one of which is directly behind the 75 other in the drawing, the upper ends of the two cores being connected by a backstrap 4.

The magnet core 3 is provided with two windings 5 and 6 which are held in place by 80 disks 14 of non-magnetizable material located at the ends of the core. Winding 5, which I will call the "pick-up" winding, is of comparatively low resistance, while winding 6, which I will call the "holding" winding, is of comparatively high resistance. It 85 is understood that the other core, which is not shown, carries two similar windings, and that the two pick-up windings are connected in series as are also the two holding windings. To simplify the disclosure, however, 90 I will hereinafter neglect the core and windings which are not actually shown in the drawing.

Magnet E controls an armature 7 which is pivotally mounted in brackets 8 attached to the polepieces 3^a. The usual core pins 9 are provided to keep the armature a certain distance away from the polepieces when in the fully closed position.

The armature 7 is provided with insulation studs 13 which carry a contact operating bar 10. This bar controls a "front" contact comprising a flexible finger 11 attached to the bar, and a fixed member 12 mounted in the plate 1, it being understood 105 110

that this contact is closed when the armature is closed, and open when the armature is open, in accordance with usual and well known practice.

5 The holding winding 6 is provided with a low resistance shunt which includes a contact C also controlled by the bar 10. This shunt is from the upper end of winding 6 through wires 22 and 24, terminal post 25, 10 flexible connector 26, bar 10, contact C, and wire 27 to the lower end of winding 6. Contact C comprises a flexible spring 15 attached to the bar 10 and having a contact tip 15^a adapted to engage with an anvil 16^a on a 15 bracket 16, this bracket being suspended from the top plate 1. The contact C is arranged to close when the armature reaches a predetermined intermediate position in its opening movement, and it then remains 20 closed during the remainder of this movement and at least until the armature returns to the same intermediate position while closing. The relative positions of the parts of contact C and the associated elements of the 25 relay when this contact closes are as shown in Fig. 3. The point at which contact C closes is so chosen that when the armature reaches this point it cannot be returned to the closed position by current of "release" 30 value in the pick-up winding 5. This point is usually close to the lowest or fully open position of the armature.

If contact C were allowed to open when the armature 7 reaches the intermediate position referred to above during the return or closing movement, the armature would be apt to drop part way back and so cut out the holding winding, whereupon it would again move toward the closed position 35 under the influence of the pick-up winding, this operation resulting in bobbing or chattering of the armature. To avoid this, I provide means for keeping contact C closed on the up stroke of the armature until the latter has passed well beyond the aforesaid intermediate position, and preferably until the armature is almost in its fully closed or highest position. This means, as here shown, comprises an auxiliary 40 armature 17 attached to the outer or free end of contact spring 15, and coacting with a permanent magnet P which I will term the auxiliary magnet. When the main armature 7 is in the lowest or fully open 45 position, auxiliary armature 17 rests on the polepieces of magnet P, the parts then being in the relative positions in which they are shown in Fig. 4. Then as the main armature 7 moves upwardly toward its 50 closed position, the flexible contact spring 15 is held closed against contact anvil 16^a due to the magnetic attraction of auxiliary armature 17 by magnet P. When the armature 7 reaches the point at which it is desired 55 that contact C should open, an exten-

sion 10^a on the operating bar 10 engages with auxiliary armature 17 and raises this armature away from magnet P, so that contact C then opens with a snap action. The relative positions of the parts just before 70 contact C opens are as shown in Fig. 5. The point at which contact C opens is so chosen that with current of pick-up value supplied to magnet windings 5 and 6 the main armature 7 will not drop back but will continue 75 to its fully closed position.

As here shown, the windings of relay R are included in a track circuit which comprises an insulated section of railway track A—B. When the shunt around the holding 80 winding 6 is open, this track circuit is from battery 20 through upper track rail 19, wire 21, pick-up winding 5, holding winding 6, wires 22 and 23, and lower track rail 19 to battery 20. When contact C is closed, 85 the circuit is the same except that the low resistance shunt around the holding winding 6 is closed.

The operation of the entire apparatus is as follows: When the track section A—B is 90 unoccupied, current of maximum value is supplied to windings 5 and 6 in series, and armature 7 is then closed as shown in Fig. 1. When a train, represented by a pair of wheels and axle T, enters the track section 95 A—B, the current supplied to winding 5 is reduced to at least the release value, whereupon armature 7 opens, thereby closing contact C and so shunting out the high 100 resistance holding winding 6. When the train T passes out of section A—B, the current supplied to the pick-up winding 5 rises to at least the pick-up value, so that armature 7 then moves toward the closed 105 position. Just before reaching this position contact C opens, thereby opening the shunt around the holding winding 6, but the current which flows in the two windings 5 and 6 in series is of sufficient value to continue the movement of armature 7 to its 110 fully closed position and to hold it in such position.

Although I have shown a magnetic device for holding contact C closed, it is understood that any other suitable device might 115 be provided for this purpose without departing from the scope of certain of the appended claims.

Although I have herein shown and described only one form of relay and circuits 120 therefor embodying my invention, it is understood that various changes and modifications may be made therein within the scope of the appended claims without departing from the spirit and scope of my invention. 125

Having thus described my invention, what I claim is:

1. In combination, a relay having an energizing winding, a circuit for said winding including a resistance, a shunt around said 130

resistance, and means for closing said shunt when the armature of the relay reaches almost the fully opened position, but for preventing said shunt from opening until the armature reaches almost its fully closed position.

2. In combination, a relay having an energizing winding, a circuit for said winding including a resistance, a shunt around said 10 resistance including a contact which closes when the armature of the relay reaches almost the end of its stroke while opening, and means for keeping said contact closed until the armature reaches almost the end 15 of its stroke while closing.

3. In combination, a relay having an energizing winding, a circuit for said winding including a resistance, a shunt around said 20 resistance, and means for closing said shunt when the armature of the relay reaches almost the end of its stroke while opening, and for opening said shunt when the armature reaches almost the end of its stroke while closing.

4. In combination, a relay having an energizing winding, a circuit for said winding including a resistance, a shunt around said 25 resistance, means operating while the armature of the relay is opening to close said shunt when the armature reaches such 30 position that it cannot be closed by current of release value in the energizing winding, and means for keeping said shunt open until the armature has passed said position while 35 closing.

5. In combination, a relay having an energizing winding, a circuit for said winding including a resistance, a shunt around said 40 resistance including a contact which closes while the armature of the relay is opening when the armature reaches such position that it cannot be closed by current 45 of release value in the energizing winding, and means for keeping said contact closed until the armature has passed said position while closing.

6. In combination, a relay having an energizing winding, a circuit for said winding including a resistance, a shunt around 50 said resistance, and means for closing said shunt at one position of the relay armature while the latter is opening, and for opening said shunt when the armature has passed said position while closing.

7. In combination, a relay having an energizing winding, a circuit for said winding including a resistance, a shunt around 55 said resistance including a contact which closes when the relay armature is in an intermediate position while opening, and means for holding said contact closed until the armature has passed said intermediate position while closing.

8. In combination, a relay having an energizing winding and a main armature, a 60

contact comprising a fixed member and a flexible spring carried by said armature and arranged to engage with said fixed member when the armature reaches an intermediate position while opening, an auxiliary armature carried by said contact spring, an auxiliary magnet coöperating with said auxiliary armature to hold said contact closed until the main armature has passed said intermediate position while closing, a circuit 70 for said energizing winding, and means controlled by said contact for increasing the resistance of said circuit when the contact is open and decreasing the resistance of said circuit when the contact is closed. 80

9. In combination, a relay having an energizing winding, and a main armature, a contact comprising a fixed member and a flexible spring carried by said armature and arranged to engage with said fixed member 85 when the armature reaches an intermediate position while opening, an auxiliary armature carried by said contact spring, an auxiliary magnet coöperating with said auxiliary armature to hold said contact closed, a member attached to said main armature for releasing said contact spring when the main armature has passed beyond said intermediate position while closing, a circuit for said energizing winding, and means controlled by said contact for increasing the resistance of said circuit when the contact is open and decreasing the resistance of said circuit when the contact is closed. 95

10. In combination, a relay having an energizing winding and a main armature, a contact comprising a fixed member and a flexible spring carried by said armature and arranged to engage with said fixed member when the armature reaches an intermediate 100 position while opening, means for holding said spring in engagement with said fixed contact member until said armature has passed said intermediate position while closing, a circuit for said energizing winding, 105 and means controlled by said contact for increasing the resistance of said circuit when the contact is open and decreasing the resistance of said circuit when the contact is closed. 110

11. A relay having a pick-up and a holding winding, a shunt for said holding winding including a contact which closes when the armature is near the end of its stroke while opening, and means for keeping said 115 contact closed until the armature is near the end of its stroke while closing.

12. A relay having a pick-up and a holding winding, a shunt for said holding winding, and means for closing said shunt when the armature is near the end of its stroke while opening, and for opening said shunt when the armature is near the end of its stroke while closing. 125

13. A relay having a pick-up and a hold- 130

ing winding, a shunt around said holding winding, and means for closing said shunt at one position of the armature while the latter is opening, and for opening said shunt when the armature has passed said position while closing.

14. In combination, a relay having an energizing winding, a circuit for said winding, and means controlled by the armature 10 of said relay for decreasing the resistance

of said circuit when the armature reaches a given point while opening, and for increasing the resistance of said circuit after the armature has passed said point while closing.

In testimony whereof I affix my signature 15 in presence of two witnesses.

CLINTON O. HARRINGTON.
